UNITED STATES PATENT OFFICE.

JOHN McHENRY AND JAMES O'DONNELL, OF CATAWISSA, MISSOURI.

BAND-CUTTER AND FEEDER FOR THRASHING-MACHINES.

SPECIFICATION forming part of Letters Patent No. 317,401, dated May 5, 1885.

Application filed November 26, 1884. (No model.)

To all whom it may concern:

Be it known that we, JOHN McHENRY and JAMES O'DONNELL, citizens of the United States of America, residing at Catawissa, in

5 the county of Franklin and State of Missouri, have invented certain new and useful Improvements in Band-Cutters and Feeders for Thrashing-Machines; and we do hereby declare the following to be a full, clear, and exact 10 description of the invention, such as will enable others skilled in the art to which it appertains to make and use the same, reference being had to the accompanying drawings, and to letters or figures of reference marked thereon, which 15 form a part of this specification.

Our invention relates to certain new and useful improvements in band cutting and feeding attachments for thrashing-machines, the same being designed more especially as an 20 improvement upon Patent No. 253,815, dated February 14, 1882, and Patent No. 173,586, dated February 15, 1876; and our invention consists in the construction and combination of the parts, as will be hereinafter fully set 25 forth, and specifically pointed out in the claims.

In the accompanying drawings, which illustrate our invention, Figure 1 is a sectional view of the attachment. Fig. 2 is a side view, 30 and Figs. 3 and 4 are detail views of parts.

A represents a suitable supporting-frame, the top beam, A', of which extends beyond the front supporting legs, and carries a platform, B, above which is located the feed-apron C. The transverse shaft *a* at the forward part of the machine is supported in journals attached to the under side of the beams A', while the lower shaft is secured in journals attached to the upper side of the beams A'', 35 which are located under and are parallel with the upper beams, A'. The lower shaft, *a'*, is provided outside of the supporting-frame with with a pulley, *b*. To the upper part of the supporting-frame are rigidly attached side pieces, D, and a top, D'. The side pieces D are cut away for the reception of disks E on the ends of the shaft F, thus providing a depending portion, *d*, to the lower front ends of which are attached angular metallic strips *e*, 40 which project inwardly over the edges of the feed-apron. The shaft F is journaled between uprights located and attached between the

horizontal beams A' A''. On the part of the shaft F which extends beyond the frame is secured a pulley, *f*, and means for rotating said 55 shaft.

At the lower end of the feed-apron is secured a transverse board, G, which is provided with upwardly-projecting pins *g*, between which pass pins *e'*, attached to transverse bars *f'*, which are secured to the disks E. 60

To the upper part of the frame is secured a cover, H, by means of arched bars H', which are rigidly secured to the side pieces *h*. These arched bars are provided at one end with 65 tongues *i*, which fit into blocks I, which are centrally recessed, as shown at *i'*. The forward ends of these arched bars lie flat upon the upper edge of the beams A', and engage with upwardly-projecting pins attached thereto, 70 said pins being indicated by the letter *k*. The upper portion of the arched bars H', adjacent to the pins *k*, are provided with recesses *k'*, which form a part of the journal for the shaft J, blocks K having recesses which 75 form the upper part of the journal, said blocks being provided with screws or bolts *l*, which pass through the blocks and end of the arched bar, so as to enter the upper portion of the beam A', thus providing a means for holding 80 the hinged cover in place.

The ends of the arched bars H', adjacent to where they are pivoted to the blocks I, are provided with inclined projecting portions *n*, which, when the cover is raised, will abut 85 against the top edges of the block I and form a rest or bearing, so that said top will be held in an almost vertical position, and will prevent said cover from being thrown entirely back. The inclined board *m'* of the top will 90 also rest upon the board D' and relieve the pintles of the weight of the cover when said cover is raised.

To the shaft J are secured knives *j*, the cutting-edges of which are curved, as shown, and 95 this shaft has attached at its ends outside of the frame pulleys *J' j'*, which are of different diameters, as shown in Fig. 3. The shafts *a', F, J* are connected to each other by belts. The belt *N* passes over the pulley on the end 100 of the shaft F, and from thence over the pulley *J'*. A belt, *N'*, which is crossed, passes over the pulleys *j'* *b*.

The sheaves are fed upon the apron, and

the knives will cut the bands as they are carried forward, and after leaving the rotary feed-apron the straw will be separated and carried forward by the teeth e' , and will be delivered to the thrashing-machine.

It will be seen from the foregoing that the hinged cover only carries the shaft to which the band-cutting knives are attached, and that said cover is thoroughly braced against both lateral and longitudinal movement, as the arched bars, which are rigidly attached to the sides of the cover, snugly embrace the side pieces D of the frame, and when the cover is lowered the ends of the arched pieces are braced by the blocks I. By providing this hinged cover, easy access may be had to the knives when it is desired to adjust or sharpen the same.

The transverse bar G is raised slightly above the inclined bottom B under the rotary feed-apron, so that any refuse which may fall or be carried upon the board B will be discharged through this opening.

We claim—

1. In a band-cutting and feeding attachment for thrashing-machines, the combination, with the main frame, of the traveling feed-

apron, a hinge cover or frame, and a transverse shaft having curved knives mounted in said cover near its front end, said knives operating over said feed-apron, the parts being combined substantially as shown, and for the purpose set forth.

2. The combination of an endless apron, the transverse bar with parallel projecting teeth, the distributing-drum with teeth e' , and the hinged frame, carrying at its front portion a shaft with cutting-knives which operate upon the endless apron substantially as shown, and for the purpose set forth.

3. The combination of the main frame, the recessed bearing-blocks I, a frame and cover, H, the arched arms or bars H' rigidly adapted thereto and pivoted in the recessed bearing-blocks K, and shaft J, substantially as set forth.

In testimony whereof we affix our signatures in presence of two witnesses.

JOHN McHENRY.
JAMES O'DONNELL.
